UNITED STATES PATENT OFFICE.

WALTER FERRIS AND WILLIAM ELSTON MAGIE, OF SOUTH MILWAUKEE,
WISCONSIN, ASSIGNORS TO THE BUCYRUS COMPANY, OF SOUTH MIL-
WAUKEE, WISCONSIN, A CORPORATION OF WISCONSIN.

A-FRAME.

No. 827,794.

Specification of Letters Patent.

Patented Aug. 7, 1906.

Application filed October 20, 1905. Serial No. 283,562.

To all whom it may concern:

Be it known that we, WALTER FERRIS and WILLIAM ELSTON MAGIE, citizens of the United States, residing at South Milwaukee, county of Milwaukee, State of Wisconsin, have invented certain new and useful Improvements in A-Frames; and we do hereby declare the following to be a full, clear, and exact description of the invention, such as will enable others skilled in the art to which it appertains to make and use the same.

This invention relates to A-frames which are employed to support the guys for booms of steam-shovels, dredges, and the like.

The object of the invention is to render the parts readily interchangeable, so that repairs will be facilitated, and to provide improvements in structures of the character described, as will be hereinafter set forth.

In the accompanying drawings, which illustrate the invention, Figure 1 is a top plan view of the head of an A-frame. Fig. 2 is a side elevation of the same. Fig. 3 is a front elevation of a head as shown in Figs. 1 and 2 with a modified lubricating means. Fig. 4 is a section on the line 4-4 of Fig. 3. Fig. 5 is a front elevation, on a smaller scale, of an A-frame including the legs and head. Fig. 6 is a side elevation of the same. Fig. 7 is a side view of a leg, and Fig. 8 is a front view of the upper portion of an A-frame which is slightly modified.

Referring to the drawings, the A-frame comprises a head B and converging legs C and D. Suitably-mounted lugs E and F support the frame.

The head B consists of the usual journal 1, to which the guy for the boom is secured. The back 2 and walls 3, 4, 5, and 6 form channels for receiving the legs, and the back may be cored out, as shown, for the sake of lightness. The eye 7, extending from the back of the head, provides a means for securing the guy for anchoring the A-frame.

As in Figs. 1 and 2, a groove 8, constituting an oil-chamber, may be formed in the upper part of the journal, and holes 9 serve to lead the oil from the chamber to the bearing-surface. A modified means of lubrication is shown in Fig. 3, in which the center of the journal is cored out to form an oil-chamber 10, which communicates with the bearing-surface through holes 11. At the lower ends

of the leg-receiving channels flanges 12, 13, 14, and 15, through which holes are made, 55 are provided to facilitate the attachment of leg-securing caps 16 and 17 to the head. In order that the legs when secured may be firmly held, channels 18 may be provided for securing filling material, such as shims 19 or 60 Babbitt metal 31, in position about the legs.

The legs C and D are shown as being of square section; but the section may have other shapes. The extremities of each leg are bent into parallel planes, and parallel 65 holes are bored in the bent extremities.

In assembling the frame the two converging ends of the legs are introduced into the leg-receiving channels in the head. A pin 20 is then passed through the holes in the leg 70 extremities within the head and suitable holes formed in the head itself. This pin may be secured by any means, such as nuts, as shown, and extends along the plane of the legs—that is, it lies in or is parallel to that 75 plane. The legs are further secured to the head by means of caps 16 and 17, which are secured to the head at the lower ends of the channels, being drawn down against the legs by bolts 21, 22, 23, and 24 passing through 80 the holes in the flanges 12, 13, 14, and 15. The leg is thus forced firmly against the back of the head. The firmness of connection between the legs and the head is still further enhanced by inserting a filling—such as 85 shims or Babbitt metal, before referred to—between the legs and the channel-walls. The lower extremities of the legs may be secured to the lugs E and F by means of pins 25 and 26, extending through holes in those extremities and suitable holes in the lugs. 90

Fig. 8 illustrates a modification of the apparatus described, but which departs in no essential features therefrom. The head is divided, so that the leg-receiving channels are 95 formed in separated members, and each of the legs is secured by means of a separate pin, the two pins differing from the pin 20, hereinbefore described, only in that they are separated in the middle of the head. The two 100 pins in the one case are the equivalent of the one pin in the other. In Fig. 8 the means for securing the pins within the head comprise plates 27 and 28, pivoted upon screws 29 and 30, so that they may either cover the 105 pin-holes or not, as desired, they being held in

any desired position by tightening the pivot-screws.

Without being limited to the precise construction shown, what we claim is—

- 5 1. In an **A**-frame, the combination with the head of two separately-removable converging legs and a securing-pin extending along the plane of said legs.
- 10 2. In an **A**-frame, the combination with the converging legs of the head having channels for receiving the legs, a pin extending along the plane of said legs for securing said legs in the upper ends of said channels, and means for securing said legs in the lower ends of said channels.
- 15 3. In an **A**-frame, the combination with the separately-removable converging legs of the head, a securing-pin extending through said head and legs along the plane of said legs, and means at the lower part of the head for securing the legs thereto.
- 20 4. In an **A**-frame, the combination with converging legs of a head having channels for receiving said legs, a securing-pin extending

along the plane of said legs and through said head and legs at the upper ends of said channels, removable cap-pieces secured to said head at the lower ends of said channels and filling about said legs.

5. In an **A**-frame, the combination with converging legs having their extremities bent into parallel planes, each of said legs having a hole in each extremity and the holes in a leg being parallel, a head, a pin passing through said head and a hole in an extremity of each of said legs a support, and pins passing through the other holes in said legs and said support.

6. A head for an **A**-frame having an oil-chamber formed therein, a bearing-surface and holes connecting said chamber with said surface.

In testimony whereof we affix our signatures in presence of two witnesses.

WALTER FERRIS.

WILLIAM ELSTON MAGIE.
